TIME RECORDER MECHANISM

Elmer G. Streckfuss, Cincinnati, Ohio, assignor
to The Cincinnati Time Recorder Company,
Cincinnati, Ohio, a corporation of Ohio

Application November 20, 1935, Serial No. 50,683

9 Claims. (Cl. 234—43)

My invention relates to time recorders, and more particularly to certain mechanisms therein which have for their purpose the indication of whether the time punched is "in" or "out" time. Such indication may be made in various ways, of which I have illustrated and described two. In one of these, a two color ribbon is used, and means are provided to shift the ribbon so as indicate "out" time in a different color than "in" time. In another there is provided a movable type block, adapted when in one position to print "in", and in another to print "out". It may even be desirable to provide both types of indications, so that "in" time will be marked "in" and be printed in black, while "out" time will be marked "out" and be printed in red. Both mechanisms are actuated in the same way, and it is therefore a matter of choice whether one or both indications are used. The use of both indications, however, provides an additional safeguard against tampering with a view to obtaining a false impression on the card.

Normally the first time printed on the card will be "in" time, the second will be "out" time, the third, "in" time again, and so forth. For this reason it is desirable to provide means whereby the mechanisms will be so set that the words "in" and "out" and the colors red and black will be printed alternately on each card.

With the above factors in mind, it is an object of my invention to provide mechanism for a time recorder whereby a two-color ribbon will be shifted for alternate impressions upon a card, and whereby such shifting will be accomplished automatically.

It is another object of my invention to provide mechanisms whereby the first, third, and other odd numbered impressions upon a card for a given day will be marked "in", and whereby the even numbered impressions will be marked "out", and whereby these mechanisms will be fully automatic.

Further it is an object of my invention to provide means actuated by the individual card at alternate registrations to put into operation the devices above referred to.

These and other objects of my invention which will be set forth hereinafter or will be apparent to one skilled in the art upon reading these specifications, I accomplish by that certain construction and arrangement of parts of which I shall now describe a preferred embodiment. Reference is now made to the drawings which form a part hereof and in which:

Figure 1 is a perspective view of the mecha-

nisms, with parts of the framework removed for greater clarity.

Figure 2 is an elevational view of the lost motion device which insures a complete operation of the block and ribbon mechanisms before a record is made, as seen from the left of Figure 1, with parts of the framework removed for greater clarity.

Figure 3 is an elevational view of the ribbon shifting mechanism as seen from the right of Figure 1 with parts of the framework removed for greater clarity.

Figure 4 is a front view of an exemplary card with six time records.

Figure 5 is a similar view of a card with seven time records.

Briefly in the practice of my invention I provide a time recorder of the notch cutting type, which is described and claimed in United States Patent No. 1,731,550, dated October 15, 1929, in my name. In this type of recorder a small notch is cut in a lower corner of the card at each recording operation at a point just above an abutment which serves to locate the card. By these means the card comes to rest in the recorder at a lower point each time, during any one day, whereby the time records on the card are in the normal position for subtraction by the time-keeper. I employ this change of position of the card to put into operation the shifting mechanisms as will hereinafter be described. This recorder is also of the shifting tray type, disclosed and claimed in United States Patent to Yates, No. 1,689,905, dated October 30, 1928, wherein the card tray shifts laterally each day, and after the last shift returns automatically to the initial position. It is of course understood that the type of machine to which my invention may be applied is not limited to the specific type which I have above described, and that this type of machine has been selected for purposes of illustration only.

In the drawings, 1 indicates the hammer shaft, 2 the card tray, and 3 the rod upon which the card tray is shiftably mounted. Immediately behind the card tray 2 is the ribbon guide 4, which is mounted upon the frame member 5 for slideable vertical movement. A shaft 6 which is oscillated by the operating handle at each recording operation, is provided with two rearwardly extending arms 7 and 8, which are connected by a cross bar 9. The punch mechanism and the means for locating the card are mounted on a carriage 11, which carriage is slidably mounted on the shafts 1 and 6. Movement of the carriage

51 is accomplished by means of the lever 52 and is proportional to the movement of the card tray 2. The lever 52 is pivoted at its lower end in a lug on the frame of the machine and is connected to 5 the carriage 51 by means of a screw 51a extending through the slot 52a. At its upper end the lever 52 is linked to the card tray 2. Thus any movement of the card tray 2 produces a decreased but proportional movement of the carriage 51 through the action of the lever 52.

10 The carriage 51 carries a die plate 53 and a rocking punch plate 54 pivoted thereon at 55. The plate 53 moves in a path just below and just outside of the lower mouth of the card tray. In 15 the machine illustrated the punch plate may be actuated by the cross bar 9 through the link 56. To determine the vertical position of the card a stop lever 57 is carried by the bracket 58 which is fixed on the carriage 51. One edge of the 20 punch plate overhangs the stop lever 57 so as to cut away the card a definite amount directly above the lever.

25 All the above described mechanisms are found in the patents above referred to and form no part of this invention. They are mentioned only in order to assist one skilled in the art in orienting himself as to the location of my novel mechanisms with respect to the rest of the machine.

30 I have pivoted on the shaft 6 a pair of arms 10 and 11, which are connected at their extremities by the rods 12 and 13. This assembly is urged in a counter-clockwise direction as seen in Figures 1 and 3, by a small spring 14, which is attached to the shaft 6 by means of a hook 15. Between the rod 12 and the shaft 16, which carries some of the gears for turning the time wheels, I suspend a linkage comprising the members 17, 18, and 19. Mounted upon the link 17 is a follower member 20, which may be adjusted toward the right or left as seen in Figures 1 and 3, by means of the screws 20a and the slot 20b. The follower member 20 extends downwardly to the extent that it is urged by the spring 14 against the cross bar 9.

45 Riveted or otherwise fastened to the movable card tray is a small bracket 21, to which the ears 22 of a pin carrier 24 are hinged by the pin 23. At its end farthest removed from the hinge, the carrier 24 bears a pin 25. On its rear side, the carrier 24 bears a lug 26 through which the rod 12 passes. The operation of this part of the mechanism is as follows: When the operator pulls on the operating handle 49, the shaft 6 and therefore the members 1, 8, and 9 are rocked 50 in a counter-clockwise direction as seen in Figures 1 and 3; if there is no obstruction to the forward movement of the pin 25, the tension in the spring 14 will urge the assembly 10-11-12-13-17-18-19-20 toward the left as seen in Figures 1 and 3, the member 20 following the rod 9; if, however, the pin 25 meets with an obstruction such as an imperforate card, the pin 25 cannot move forward, with the result that the member 20 will not be permitted to follow the rod 9 under tension 55 of the spring 14, and the linkage 17-18-19 will remain in the position shown.

Toward the rear of the frame member 5 is journaled a cross shaft 27, which is adapted to be urged by spring 34 in a clockwise direction as seen in Figures 1 and 3, as will hereinafter be described. Movement of the shaft 27 is adapted to rock the shaft 28 through the linkage 29-30-31. It will be noted that the curved link 29 passes underneath the member 19. The member 75 19 is provided with a trigger portion 19a, which

is adapted to abut a small lug 29a on the member 29 which projects into the path of the trigger 19a. The connection between this part of the mechanism and that just described will now be clear; when the linkage 17-18-19 is permitted 5 to swing to the left, the trigger 19a will clear the lug 29a, permitting the link 29 to rock upwardly, thereby rocking the shaft 28 in a clockwise direction.

10 Before proceeding to a description of the mechanisms actuated by the rocking of the shaft 28, I shall briefly describe how the shaft 27 is rocked upon manipulation of the operating handle. Referring to Figure 2, which is a view looking at the other end of the shaft 27, when the operating handle 49 is actuated, the rod 32 is moved in the direction of the arrow. The end of the rod 32 is bent over at right angles to the plane of the drawings and passes through the slot 33a in the lever 33, which is loosely mounted on the 15 shaft 27. Collars 32a hold the end of the arm 32 within the slot 33a. When the end of the rod 32 abuts the upper end of the slot 33a, the lever 33 will be rocked in a counterclockwise direction. Now if the trigger 19a has been moved out 20 of the way of the lug 29a, by reason of the fact that the pin 25 did not meet with an obstruction, the tension of the spring 34 will cause the arm 35, which is fast on the shaft 27, to rock in a counter-clockwise direction as seen in Figure 2, 30 or clockwise, as seen in Figures 1 and 3. The end 33b of the lever 33 is connected by means of the rod 50 to certain parts of the time-wheel aligning mechanism as described in the patents above mentioned. It will be noted by reference 35 to the aforesaid patents, that the shaft 6 begins to rock as soon as the operating lever is depressed, that is, at the same instant that the rod 32 begins to move. The purpose of the slot 33a, therefore, is to permit the trigger 19a to clear the lug 29a, 40 provided there is no obstruction to the forward movement of the pin 25, before the shaft 27 is rocked. If the pin 25 meets with an obstruction, the arm 35 will not follow the arm 33, but the latter is permitted to continue to perform its 45 function by the extension of the spring 34.

Up to this point, the mechanism is the same whether only the ribbon shift is to be used, or only the shifting "in" and "out" printing block, or both. Referring now to Figure 1 for a description of the printing block shifting mechanism, fixed on the shaft 28 is an arm 38, to the end of which is fastened a member 36. The lower end of the member 36 is provided with an inverted U-shaped slot 36b which is adapted to ride on a bushing 37a on the shaft 37, which carries the time printing wheels. Formed on the lower end of the member 36 adjacent the slot 36b is the "in" and "out" printing block 36a, which is normally positioned to print "in". Upon motion 55 of the mechanism as described hereinabove, the shaft 28 will rock in a clockwise direction, elevating the arm 38 and the block 36a, which will then come into position to print "out".

60 In Figure 3 I have shown the ribbon guide 4 fastened to the frame member 5 by screws 4a which pass through vertical slots in the guide, whereby the guide 4 is capable of vertical shifting. In this case I provide an arm 39 similar to 70 arm 38, which is connected by the link 40 to the lever 41 which is fixedly mounted on the shaft 37. Front end of the lever 41 projects into a slot 41a in the ribbon guide, so that as the shaft 28 is rocked in a clockwise direction, the lever 41 is 75

rocked counterclockwise, whereby the ribbon guide 4 is shifted downwardly.

As before mentioned, it is of course possible to use either or both the ribbon shift and the printing block shift. Referring now to Figures 4 and 5, I have illustrated two exemplary cards upon which several recordings have been made. It will be noted that the cards are provided with perforations 42, and that these perforations are spaced apart vertically the distance of two notches, one notch being the difference between the notches 43 and 46. It is to be understood that the long notch 44 represents actually four notches in succession, the notch 45 is really two notches in succession, and the notch 46 is three notches in succession. Furthermore the first perforation at the bottom of the card is so spaced that it does not come into operative position until the second recording, when the first notch has already been cut. The operation of the card is this: when a new card is inserted into the tray 2, it is so positioned that the pin 25 abuts the card between the bottom edge and the first perforation 42; a record is then made and the first small notch is cut, but in the meantime the pin 25 cannot move forward and a normal record takes place; the next time the card is inserted for record, it will be positioned one notch lower in the tray 2 as a result of the notch which was cut in it by the previous recording, which will enable the pin 25 to pass through the lowest perforation 42 and cause the record to be marked "out", or be printed in a different colored ink, or both; the third time the card is inserted, there will be a repetition of the first time, and so forth, so that the record will be printed "in" and "out", or red and black, or both, alternately. It is of course understood that on the following day the card tray is automatically shifted to print in the next column, and a new series of notches is started. In Figure 4, four records were made the first day, and two the second; if two more records were to be made on this card, there would appear a single notch double the width of notch 44. The notches need only be wide enough to provide an abutment portion.

It is to be understood that the type of machine upon which my novel mechanisms are used forms no limitation upon my invention, and the particular machine here described was merely selected for purposes of exemplification, and that different forms of my preferred embodiment may be made without departing from the spirit of my invention.

Having now fully described my invention, what I claim as new and desire to secure by Letters Patent, is:

1. In a time recorder of the class described having an operating handle and a card tray and means in connection with the tray to position a card in one of a succession of positions, the combination of a two-color type ribbon which normally occupies a position to print one of said colors, mechanism tending to shift said ribbon to a position to print the other of said colors after a predetermined degree of movement of said handle, and means operable at alternate positions of said card in said tray as determined by said first mentioned means to release said mechanism whereby said ribbon is shifted to a position to print the other of said colors.

2. In a time recorder of the class described having an operating handle and a card tray and means in connection with the tray to position a card in one of a succession of positions, the combination of a reciprocable type block adapted in

one position to print a symbol, and in another position to print a different symbol and normally occupying a position to print one of said symbols, mechanism tending to shift said block to a position to print the second mentioned symbol after 5 a predetermined degree of movement of the operating handle, and means operable at alternate positions of said card in said tray as determined by said first mentioned means, to release said mechanism, whereby said type block is shifted 10 to a position to print said second mentioned symbol.

3. In a time recorder of the class described having means for making a record and mechanism for changing the character of said record, 15 an operating handle and a card tray and means in connection with the tray to position a card in one of a succession of positions, said card being provided with a row of perforations spaced apart twice the distance of displacement of the card 20 in the tray for successive recordings; a pin, and means for urging it against said card upon operation of said handle, so that it will pass into one of said perforations when the card is so positioned that one of the perforations is in registry with 25 said pin, said pin adapted upon entry into one of said perforations to enable said mechanism to function for the purpose of changing the character of the record.

4. In a time recorder of the class described 30 having an operating handle and a card tray and means in connection with the tray to position a card in one of a succession of positions, said card being provided with a row of perforations spaced apart twice the distance of displacement of the 35 card in the tray for successive recordings, and a two-color type ribbon; a pin, and means for urging it against said card upon operation of said operating handle, so that it will enter one of said perforations when the card is so positioned that 40 one of them is in registry with said pin, and means operative upon entry of the pin into one of said perforations for shifting said ribbon.

5. In a time recorder of the class described having an operating handle and a card tray and 45 means in connection with the tray to position a card in one of a succession of positions, said card being provided with a row of perforations spaced apart twice the distance of displacement of the card in the tray for successive recordings, and a 50 symbol type block; a pin, and means for urging it against said card upon operation of said operating handle, so that it will enter one of said perforations when the card is so positioned that one of them is in registry with said pin, and means 55 operative upon entry of the pin into one of said perforations for shifting said symbol type block.

6. In a time recorder of the class described having means for making a record and mechanism for changing the character of said record, an 60 operating handle and a card tray and means in connection with the tray to position a card in one of a succession of positions, said card being provided with a row of perforations spaced apart twice the distance of displacement of the card in the tray for successive recordings; a pin, and means for urging it against said card so that it will enter one of said perforations when the card is so positioned that one of them is in 70 registry with said pin, an abutment to restrain the movement of said pin but which is retracted upon actuation of said operating handle to permit movement of said pin, said pin upon entry into one of said perforations adapted to enable 75

said mechanism to function for the purpose of changing the character of the record.

7. In a time recorder of the class described having an operating handle and a card tray and means in connection with the tray to position a card in one of a succession of positions, the combination of a two-color type ribbon which normally occupies a position to print one of said colors, mechanism actuated by said operating handle through a delayed action connection tending to shift said ribbon to a position to print the other of said colors, and means operable at alternate positions of said card in said tray to release said mechanism whereby said ribbon is shifted to a position to print said other color.
8. In a time recorder of the class described having an operating handle and a card tray and means in connection with the tray to position a card in one of a succession of positions, the combination of a reciprocable type block adapted in one position to print a symbol, and in another position to print a different symbol and normally occupying a position to print one of said symbols, mechanism actuated by said operating handle through a delayed action connection tending to shift said block to a position to print the second mentioned symbol, and means operable at alter-

nate positions of said card in said tray to release said mechanism whereby said type block is shifted to a position to print the second mentioned symbol.

9. In a time recorder of the class described having an operating handle and a card tray and means in connection with the tray to position a card in one of a succession of positions, said card being provided with a row of perforations spaced apart twice the distance of displacement of the card in the tray for successive recordings, a reciprocable type block adapted in one position to print a symbol, and in another position to print a different symbol and normally occupying a position to print one of said symbols, and a two-color type ribbon which normally occupies a position to print one of said colors; a pin, and means for urging it against said card upon operation of said operating handle, so that it will enter one of said perforations when the card is so positioned that one of them is in registry with said pin, and means operative upon entry of said pin into one of said perforations to shift said type block to a position to print said second mentioned symbol, and to shift said type ribbon to a position to print the other of said colors.

ELMER G. STRECKFUSS.
